UNITED STATES PATENT OFFICE.

ARVIN GUSSA, OF ROSWELL, NEW MEXICO.

OVEN.

Application filed June 11, 1921. Serial No. 476,782.

To all whom it may concern:

Be it known that I, ARVIN GUSSA, a citizen of the United States, and a resident of Roswell, in the county of Chaves and State of New Mexico, have invented a new and Improved Oven, of which the following is a full, clear, and exact description.

This invention relates to improvements in ovens, particularly to an oven wherein the shelves are automatically pulled out when the oven door is open.

With the majority of ovens now employed, it is necessary when inserting material in the oven or removing material therefrom, to expose the hands to the intense heat of the oven. It has frequently happened that persons have been seriously burned either while inserting or removing trays or pans therefrom.

The primary object of this invention, therefore, is to overcome this inconvenience by providing an oven with a set of movable trays or shelves, the position of which is controlled by the oven door and which will automatically be moved out of the oven when the door is opened.

Another object is to provide a novel form of mechanism for actuating the shelves.

A still further object is to provide an oven, which will be simple and practical in construction, strong, durable and efficient in use, and comparatively inexpensive to manufacture.

With these and other objects in view, the invention consists in certain novel features of construction and combinations and arrangements of parts as will be more fully hereinafter described and pointed out in the claims.

In the accompanying drawings:—

Figure 1 is a view in longitudinal section on the line 1—1 of Figure 3, illustrating my improved oven with the door in closed position, the dotted lines indicating the position of the operating mechanism when the door is partially opened;

Figure 2 is a view similar to Figure 1 taken on the line 2—2 of Figure 3, illustrating the oven door in open position;

Figure 3 is a view in transverse section through the oven when the door is in open position;

Figure 4 is a view in front elevation of the oven when the door is opened; and

Figure 5 is an enlarged sectional view through the rule joint 12.

Referring in detail to the drawings, the reference numeral 1 indicates a rectangular oven open at its forward end. The open forward end of the oven is normally closed by a door 2, hinged to the floor of the oven, as indicated at 3, and adapted to swing downwardly and outwardly.

4 represents a rectangular shelf supporting frame which ordinarily supports a pair of removable shelves 5 and 6, which receive articles to be baked in the oven.

The invention in this case resides principally in the provision of means compelling the frame 4 to move out upon the door 2, when this door is opened.

Brackets 7 are secured to the floor of the oven at each side thereof. Pairs of levers 8 are pivotally connected to the brackets and to the top frame bar of the shelf supporting frame 4. A pair of jointed arms 9 comprise a pair of sections 10 and 11. The sections 10 are pivotally connected to the inner face of the oven door 2, adjacent its upper end and the sections 11 are each pivotally connected to one of the levers 8 adjacent their lower ends. Lugs 12 on the free ends of the sections 10 are engageable with the sections 11 to limit the pivotal movement of the jointed arms in one direction.

A roller or buffer 13 is carried by the forward end of the frame 4.

The oven 1 is preferably spaced slightly above the floor by depending flanges 14 and a rectangular flange 15 upon the outer face of the oven door 2 engages the ground when the door is swung open so that the inner door surface forms a continuation of the oven floor 16.

Any approved form of latch, designated 17 by the reference numeral 17, may be employed for locking the oven door in closed position.

The operation of the frame 4 when the door is swung open is as follows:

Partial opening of the door 2 straightens out the jointed arms 9, as indicated in dotted lines in Figure 1. Further movement of the door will operate to pivot the levers 8 on the brackets 7. As the upper ends of the levers 8 are pulled forwardly by the arms 9, the frame 4 will be lifted off the floor of the oven. By the time the door 2 has reached the limit of its downward movement, the arms 9 will have pulled the levers 8 to the position illustrated in Figure 2 and the frame 4 will have been swung in an arc out

of the oven and will rest upon the door 2, as indicated in the same figure. When the oven door is closed, the arms 9 and levers 8 operate to again restore the frame 4 to its normal position in the oven, as will be readily understood.

It is to be noted that the frame 4 is of any shape and construction to conveniently support the removable trays 5 and 6, the particular frame construction being immaterial to this invention.

Although I have illustrated one of the preferred embodiments of my invention, it will be evident that various slight changes and alterations might be made in the general form and arrangement of the parts described without departing from the invention and hence I do not wish to limit myself to the precise details set forth, but shall consider myself at liberty to make such slight changes and alterations as fairly fall within the spirit and scope of the appended claims.

I claim:

25 1. In an apparatus of the character described, an oven, a tray supporting frame in the oven, a door hinged to the floor of the oven and adapted to swing downwardly and outwardly, brackets secured to the floor 30 of the oven, levers pivotally connected at one end to the brackets and at their other ends to the frame, jointed arms pivotally connected to the free edge of the door and to the intermediate portions of the levers, 35 whereby opening of the door lifts the frame out of the oven and seats the same on the door.

2. In an apparatus of the character described, an oven, a tray supporting frame 40 in the oven, a door hinged to the floor of the oven and adapted to swing downwardly and outwardly, brackets secured to the floor of the oven, levers pivotally connected at one end to the brackets and at their other 45 ends to the frame, jointed arms pivotally connected to the free edge of the door and to the intermediate portions of the levers, whereby opening of the door lifts the frame out of the oven and seats the same on the 50 door, and means cushioning the seating of the frame on the door.

3. In an apparatus of the character described, an oven, a tray supporting frame

in the oven, a door hinged to the floor of the oven and adapted to swing downwardly and outwardly, brackets secured to the floor of the oven, levers pivotally connected at one end to the brackets and at their other ends to the frame, means connecting the door and levers whereby opening of the door pulls the frame out of the oven.

4. In an apparatus of the character described, an oven, a tray supporting frame in the oven, a door hinged to the floor of the oven and adapted to swing downwardly and outwardly, brackets secured to the floor of the oven, levers pivotally connected at one end to the brackets and at their other ends to the frame, jointed arms pivotally connected to the free edge of the door and to the intermediate portion of the levers whereby opening of the door pulls the frame out of the oven.

5. In an apparatus of the character described, an oven, a tray supporting frame in the oven, a door hinged to the floor of the oven and adapted to swing downwardly and outwardly, brackets secured to the floor of the oven, levers pivotally connected at one end to the brackets and at their other ends to the frame, jointed arms pivotally connected to the free edge of the door and to the intermediate portions of the levers, whereby opening of the door lifts the frame out of the oven and seats the same on the door, and means cushioning the seating of the frame on the door, said means comprising rollers carried by the frame and engageable with the door upon seating of the frame.

6. An apparatus of the character described, including an oven, a door hinged to the floor of the oven and adapted to swing downwardly and outwardly, a frame in the oven, means associated with the frame for supporting a plurality of removable shelves, means connecting the door and frame whereby opening of the door withdraws the frame from the oven, said last mentioned means comprising levers pivoted to the floor of the oven and to the frame, links pivoted to the intermediate portions of certain of the levers, links pivoted to the inner face of the door adjacent its free edge and a rule joint connecting said links.

ARVIN GUSSA.
